UNITED STATES PATENT OFFICE.

LOUIS REICHERT, OF SCRANTON, PENNSYLVANIA.

DRILLING-MACHINE.

SPECIFICATION forming part of Letters Patent No. 517,298, dated March 27, 1894.

Application filed October 12, 1893. Serial No. 487,929. (No model.)

To all whom it may concern:

Be it known that I, LOUIS REICHERT, of Scranton, in the county of Lackawanna and State of Pennsylvania, have invented a new 5 and Improved Drilling-Machine, of which the following is a full, clear, and exact description.

The object of the invention is to provide a new and improved drilling machine, which is simple and durable in construction, very effective in operation, and more especially designed for drilling small holes in glass and other substances and articles.

The invention consists of certain parts and details and combinations of the same, as will 15 be hereinafter described and then pointed out in the claims.

Reference is to be had to the accompanying drawings, forming a part of this specification, in which similar letters of reference indicate 20 corresponding parts in both the figures.

Figure 1 is a side elevation of the improvement with parts in section; and Fig. 2 is an end elevation of the same, with the spring and set screw support thrown down.

25 The improved drilling machine is provided with a suitably constructed frame A, in which is journaled a driving shaft B, provided on its outer ends with gear wheels C and C', of which the gear wheel C is provided with a 30 crank arm C², for conveniently turning the said shaft B by hand, or the said shaft may be provided with a pulley, as indicated in dotted lines in Fig. 1, to be driven by power. The gear wheels C and C' mesh in pinions D and D', respectively, secured on the outer ends 35 of spindles E and E', respectively, mounted to turn in suitable bearings in the main frame A, the said spindles being in alignment one with the other, and in their adjacent ends are 40 secured the diamond pointed drills or bits F and F', respectively, fastened in place by set screws G and G', respectively. The extreme outer end of the spindle E is pointed and engaged by a set screw H, screwing in a bracket I, 45 mounted to swing on a pivot I', secured to one end of the frame A, as plainly illustrated in the drawings.

In the bracket I is arranged a segmental notch I², adapted to be engaged by a set screw I³, screwing in the end of the frame A to hold the bracket in place at the time the set screw H engages the pointed outer end of the spin-

dle E. By this arrangement a longitudinal outward sliding of the spindle E is prevented, so as to hold its drill or bit F in contact with 55 the article to be operated on. When the set screws H and I³ are slackened, the bracket I can be swung to one side so as to conveniently slide the spindle E out of its bearing, for the removal of the drill or for other purposes. 60 The outer end of the other spindle E' is likewise formed with a point and is pressed on by the free end of a spring J, held on a pivot J', secured to the end of the frame A opposite that on which the bracket I is located. The 65 spring J may be re-inforced by a series of additional leaves J², likewise held on the pivot J' and serving to press the spindle E' inward, to feed the drill F' into the article to be drilled.

The machine is designed chiefly for boring 70 eye-glasses; and it is requisite that the pressure on the spindles be slight at the beginning of the operation, in order to avoid chipping the glass. The provision of a series of spring leaves so arranged that one may be reinforced 75 by another and thus graduate the pressure on the spindle, is therefore important.

The operation is as follows: By the operator moving the spring J, out of engagement with the spindle E', the latter can be moved 80 outward so as to permit of inserting the article to be drilled between the two drills F and F'. When this has been done, the spring J is engaged with the outer end of the spindle E', so that the latter is pressed inward to engage 85 the drill F' with one side of the article, the other side being engaged by the other drill F. When the main shaft B is rotated, the gear wheels C and C' impart rotary motion to the pinions D and D', so that the spindles E 90 and E' turn in their bearings. Now, as the two drills F and F' rotate and are in alignment with each other, they drill a hole in the article from opposite sides, it being understood that the drill F' by being pressed on by 95 the spring J fits into one side of the article and presses the latter with sufficient force to cause the article to advance on the other drill. The spindle E can be fed inward by adjusting the set screw H, but the inward movement 100 of both spindles is limited by the pinions D and D' finally abutting against the ends of the frame A. When this position is reached, the points of the drill are close together and

the hole has been drilled. The pinions D and D' have their faces made considerably wider than the gear wheels C and C', so that the pinions remain in mesh at the time the spindles E and E' are fed inward in the manner above described. When a hole has been drilled, the operator throws the spring J downward and slides the spindle E' outward to permit of conveniently removing the article.

10 Having thus fully described my invention, I claim as new and desire to secure by Letters Patent—

15 1. A drilling machine, comprising two aligned, rotatable and slidable spindles carrying drills, means for rotating the drills while moving axially, and a series of independent spring leaves acting on the outer end of one of said spindles, and said leaves being adapted to be reinforced one by another, for the 20 purpose of gradually increasing the pressure on the drill, as shown and described.

2. A drilling machine, comprising two aligned rotatable and slidable spindles, drills

held in the adjacent ends of the said spindles, and a series of spring leaves held by a 25 common pivot and separately adjustable thereon, and pressing on the outer end of one of the spindles to feed its drill into the article, substantially as shown and described.

3. In a drilling-machine of the class specified, the combination with the frame, driving shaft, and its gears, the drill-carrying spindles aligned and adapted to slide and rotate as specified, and provided with pinions having a meshing as well as sliding engagement 35 with said gears, a swinging bracket pivoted at one end of the frame, and means for locking it to said frame and pressing the spindles toward each other, whereby the spindles may be rotated while sliding and detached when 40 their work is done, as shown and described.

LOUIS REICHERT.
